of Missouri

Application September 28, 1953, Serial No. 26,967

Term of patent 7 years

(Cl. D4—3)

To all whom it may concern:

Be it known that I, Albert J. Gerber, a citizen of the United States, residing at the city of Ladue, county of St. Louis, State of Missouri, have invented a new, original, and ornamental Design for a Combination Sponge and Soap Dish or the like, of which the following is a specification, reference being made to the accompanying drawing forming a part thereof, in which:

Figure 1 is a side elevational view of a combination sponge and soap dish or the like, embodying my new design;

Figure 2 is a top plan view thereof;

Figure 3 is a front elevational view thereof; and

Figure 4 is a rear elevational view thereof.

The cake of soap disclosed in dotted lines is shown only for the purpose of illustration.

I claim:

The ornamental design for a combination sponge and soap dish or the like, substantially as shown and described.
